UNITED STATES PATENT OFFICE.

FRANK L. TIDEMAN, OF BROOKLYN, NEW YORK.

ART OF MAKING HEXAGONAL NUTS.

1,076,079.

Specification of Letters Patent.

Patented Oct. 21, 1913.

Application filed August 13, 1912. Serial No. 714,825.

To all whom it may concern:

Be it known that I, FRANK L. TIDEMAN, a citizen of the United States, residing at Brooklyn, in the county of Kings and State 5 of New York, have invented a new and useful Improvement in the Art of Making Hexagonal Nuts, of which the following is a specification, reference being made therein to the accompanying drawings.

10 This invention relates to a novel method or process including the making of peculiar blanks from round, or approximately round, metal rods, and transforming the same into hexagonal nuts; the object being 15 to afford a simple and expeditious method of manufacture; to avoid waste of material, and to reduce the cost of production of said class of nuts.

In the accompanying drawings, Figure 1 20 represents a plan view of a piece of round rod stock, and shows the manner of forming the blank therefrom. Figs. 2 and 3 represent a side view, and end view, of the primary blank, as severed from the rod or 25 bar. Fig. 4 is a cross-section at line X (on Fig. 1 or Fig. 2) and Fig. 4^a shows a similar cross-section of a blank-stock rod which is oval or approximately round; a suitable shape, but not of exactly circular 30 cylindrical cross-section. Fig. 5 represents a transverse section of the blank, as flattened from its cylindrical form, or as rendered at the second stage of the transformation, and Fig. 6 is a plan view of the same. 35 Figs. 7, 8 and 9 represent, respectively, a side, section and plan views of the nut as at the third step in the process of manipulation, and Fig. 10 illustrates the finishing or perfecting of the peripheral edges of 40 the completely shaped nut.

In my improved method of making hexagonal nuts I use, as a stock material therefor, metal bars or rods 1 of round shape, cylindrical or approximately cylindrical cross-section, and of a diameter somewhat greater than the length of one hexagonal side of the required nut; this proportion being somewhat variable, more or less, for different thicknesses of nuts. From the round rod of 50 stock, Fig. 1, a peculiar blank 2 is formed, by severing therefrom a portion of suitable length, by opposite V-shaped lateral incisions 3 entering the sides of the rod and meeting at the central axis, thus producing 55 a blank, having a cylindrical or approximately round cross-section, and wedge-

shaped angular ends 3^a, the line 5^a of the angles being upright, thereby giving to the blank an approximately hexagonal contour horizontally. The severance of the round 60 rod 1 by a V-shape incision condenses or upsets some of the metal at the outside edge 4 and stretches or draws the metal more or less near the bottom 5 of the V. The severing of the rod to form the blanks 2 can 65 be effected by various means, one practical way of doing it is to employ oppositely approaching wedge-shaped cutters 6 meeting, or nearly so, at the central axis of the rod; the rod being intermittently adjusted 70 endwise for the length of each succeeding blank as the blanks are separated therefrom. This primary blank 2 is next placed in a suitable hexagonal die or matrix where it is centrally confined by its angular ends 75 5^a, coinciding with two opposite corners of the hexagon, and is there flattened upon its top and bottom convex or rounded surfaces 7 and 8, or compressed in the direction of the line 5^a at which the inclined end surfaces meet. Preferably, and at the same 80 time a beveled or cup-shaped dépression 9 is centrally formed in each of the flattened surfaces (see Figs. 5 and 6). This second step brings the blank into a flat, practically 85 hexagonal form as an embryo nut 2^a. The next step in the process is to stamp the upper and lower flat-faces 7 and 8 with the crown-bevel or chamfer 10, and to punch through the central opening or eye 12 within the depression 9, giving the complete nut 90 form shown in Figs. 7, 8 and 9. The nut 2^a is then passed through a broaching or gaging operation, as by punching it through a cutting edged gage-die 15, for removing 95 any irregularities or bur that may have been formed thereon, and for squaring up and perfecting the sides to a true hexagonal shape. The threading of the eye 12 may be done in usual manner.

I do not claim broadly, the idea of utilizing a cup-shaped recess as a preparatory impression for the eye in the construction of nuts, as I am aware that such recesses have heretofore been adopted in a different 105 method of manufacture.

In some instances the forming of the central cup-shaped depression 9 may be omitted, as the forming of the eye 12 could be effected without said recess. But I prefer to make the recesses as a part of the 110 second step, since they serve to render the

forming of the eye easier; and also give a slight bevel or counter-bore at the edge of the eye.

By the within described method or process 5 hexagonal nuts may be economically and practically made, and with comparatively very little waste of material in their manufacture while they are produced from round, or approximately round, rod-stock.

10 What I claim and desire to secure by Letters Patent, is—

1. The improvement in the art or process of making hexagonal nuts, which consists in producing a blank directly from a rod or 15 bar of round or approximately round cross-section, by lateral V-shaped incisions at the opposite sides of the rod and meeting at the center thereof, compressing and flattening the convex upper and lower cylindrical 20 faces of the blank and at the same time forming central circular depressions in said flattened faces, then stamping the upper and lower faces to form the crowning bevel, and simultaneously punching out the central 25 eye, and subsequently perfecting the gage of the hexagonal facets.

2. The method of producing hexagonal nuts, which consists in primarily forming 30 directly from a round rod, by opposite V-shaped severance thereof, an approximately

cylindrical blank having angular ends and approximately hexagonal outline, placing said blank in a hexagonal matrix with its angular ends fitting in opposite angles thereof, and flattening the upper and lower 35 convex faces, stamping said upper and lower flattened faces to form a crowning bevel, and the central eye hole, then shaving the hexagonal faces to perfect gage and subsequently threading the eye. 40

3. In the art of making hexagonal nuts, the method which consists in producing a primary blank directly from a round or approximately round rod by oppositely directed wedge-shaped incisions that condense or 45 upset the metal at its exterior opposite sides and stretches and parts the metal along its medial line, thereby providing a transversely cylindrical blank having obtuse wedge-shaped ends; and subsequently flattening the convex upper and lower faces and spreading laterally said cylindrical 50 contour into a hexagonal form.

Witness my hand this 10th day of August, 1912.

FRANK L. TIDEMAN.
